UNITED STATES PATENT OFFICE.

ALBERT D. PURTLE, OF MARIETTA, OHIO.

CLAMP.

Application filed October 2, 1924. Serial No. 741,271.

This invention has reference to casing head clamps, and aims to provide novel means whereby a pump jack may be readily attached to a stuffing box casing head.

Another important object of the invention is to provide a device of this character including a three point suspension for securely gripping the bowl of the casing head.

A still further object of the invention is to provide a device of this character which may be readily and easily secured to a casing head, eliminating the necessity of making extensive alterations in the casing head or clamp, to position the device.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a side elevational view of a clamp constructed in accordance with the invention, showing the clamp positioned on a casing head.

Figure 2 is a plan view of the clamp.

Figure 3 is an end elevational view thereof.

Referring to the drawing in detail, the clamp includes sections 5 and 6 respectively, the sections being formed with laterally extended ears 7 which are formed with openings to accommodate the connecting bolts 8 that extend through aligning openings, to secure the sections together.

Each of the sections has its inner surface curved as at 9 to provide a surface to conform to the curvature of a casing head, so that the sections may be moved into close engagement with the casing head to accomplish the purpose of the invention.

Extending upwardly from each section and disposed at a point adjacent to the central portion of the curved surface thereof, is a finger 10 adapted to engage the casing head to which the clamp is secured. Depending from the under side of each section are flanges 11 which cooperate with the fingers 9 for gripping the casing head to which the casing head is secured, thereby providing a three point clamping construction.

The bolts 8 are provided with threaded portions 12 that accommodate the nuts 13 so that the clamping sections may be secured in position on a casing head. Extending from one of the sections are spaced ears 14 which are also formed with openings to accommodate a bolt so that a jack brace may be secured thereto.

As illustrated by Figure 1, the clamp is shown as positioned on a casing head, the casing head being indicated at 15.

From the foregoing it will be obvious that due to this construction, the casing head may be securely held into position and the construction of the clamp is such that a close-fit will be insured between the well casing head and stuffing box.

I claim:

A casing head clamp including separable sections having curved cooperating edges adapted to fit around the curved surface of a casing head, said sections having upwardly extended integral fingers arranged adjacent to the curved surfaces to engage the straight portion of a casing head, lateral apertured ears, bolts extending through the ears for securing the clamp to a casing head, upwardly extended ears forming a part of one of the sections and having openings to receive a bolt for supporting a pump jack.

In testimony that I claim the foregoing as my own, I have hereto affixed my signature.

ALBERT D. PURTLE.
